UNITED STATES PATENT OFFICE.

OLIVETTE ROMESBERG, OF GARRETT, PENNSYLVANIA.

COMBINATION TABLE AND IRONING BOARD.

Application filed March 9, 1923. Serial No. 623,961.

To all whom it may concern:

Be it known that OLIVETTE ROMESBERG, a citizen of the United States, residing at Garrett, in the county of Somerset and State 5 of Pennsylvania, has invented certain new and useful Improvements in Combination Tables and Ironing Boards, of which the following is a specification:

The present invention relates to improvements in combination tables and ironing boards and has for an object to provide an ironing board concealed within a table so that a single piece of furniture may suffice for both uses.

Another object of the invention lies in improving the construction of table tops in order to admit of the convenient and easy removal of the top to give access to the ironing board.

A further object of the invention resides in providing an improved article of furniture of this type in which provision is made for carrying irons, stands and other utensils useful in conjunction with the ironing board.

With the foregoing and other objects in view, the invention will be more fully described hereinafter, and will be more particularly pointed out in the claims appended 30 hereto.

In the drawings, wherein like symbols refer to like or corresponding parts throughout the several views,

Figure 1 is a top plan view of a combination table and ironing board constructed according to the present invention.

Figure 2 is an end view of the same.

Figure 3 is a sectional view showing the table top in partially removed position.

Figure 4 is a longitudinal section taken through the table top and showing the remainder of the table in side elevation.

Figure 5 is a longitudinal section taken through the table showing the top removed 45 and the ironing board in raised position, and

Figure 6 is a plan view of an iron holder. Referring more particularly to the drawings, 50 7 and 8 designate the end supports for the table which may be made relatively thin as indicated in Figures 4 and 5 and having

the contour or appearance represented in the end views, Figures 2 and 3. These supports of course may be varied as desired and the same are supported upon the casters 9 55 for convenience in moving the table about, although the casters of course form no essential part of the invention.

The end supports 7 and 8 are held at a predetermined distance apart by suitable 60 boards which are arranged in a definite configuration to supply strength to the structure and a container for holding irons and the like. This structure includes a bottom board 10 and the side walls 11 and 12 forming with the bottom and long box or receptacle open at its top and having the lid 13 hinged at 14 to the top of the wall 11. In conjunction with this structure are provided three reinforcing rods 15, 16 and 17. 65 These reinforcing or tie-rods are disposed in a triangular formation. The apex rod 15 is situated beneath the intermediate part of the bottom board 10 and serves to support the container, whereas the companion rods 75 16 and 17 rest within the body of the container and against the interior surfaces respectively of the walls 11 and 12 and they thus serve, in conjunction with the rod 15 to avoid any lateral movement of the receptacle upon the lower rod. The rods, as shown in Figure 5 are threaded at their ends and project into recesses made in the end supports 7 and 8, nuts 19 being threaded 80 upon the nuts within the recesses. The nuts 85 are tightened to force the supports 7 and 8 against the ends of the boards, sufficient clearance being allowed to permit of easily opening the top 13 of the box. Wooden or other knobs or plugs 20 are used to conceal the nuts and are forced into the outer 90 ends of the recesses 18.

The table top is designated at 21 and is provided with the usual side skirting boards 22 and end skirting boards 23. The end 95 boards 23 project beyond the end supports 7 and 8 and the construction is such that an appreciable space is left between the support and the skirting board at each side, in which space is placed a rail 24. These rails 100 24 support the table top 21 and in order to resist wear, said rails are provided along

their top edges with metallic or other wear plates 25. Screws or other fastenings 26 are employed to secure the rails 24 to the outer faces of the table supports 7 and 8, 5 although it will be obvious that other means of support may be employed. Now it will be noted from viewing Figures 2 and 3 that the ends of the rails 24 are inclined, such ends converging downwardly and stops 27 10 are secured to the intermediate portions of the lower edges of said rails in order to cooperate with other stops 28 carried by the end skirting boards 23. The stops 27 may be of channel iron in order to have two depending flanges, either of which may cooperate with the stop 28 without regard to whether the table top is fitted on either one side or the other of the table. The stop 28 is advantageously of angle iron construction to 15 permit the horizontal flange to project beneath the lower edge of the rail as indicated in Figure 4 and to provide a vertical flange through which fastenings 29 may be passed for securing this stop in place. The side 20 skirting boards 22 are provided with metallic or other wear plates 30 which slide upon the strips 25 upon the rails 24. Hooks 31 are carried in screw-eyes 32 secured to the inner faces of the end supports 7 and 8 25 and these hooks cooperate with eyes 33 connected to the table top. The hooks are so placed that they are accessible at the sides of the table and serve to hold the table top securely in place.

30 The ironing board is represented at 34 and it is hinged as indicated at 35 to the upper end of the table support 8. The other free end of the board 34 rests upon the upper end of the other support 7. When the 35 table top is removed the ironing board 34 may be swung up as indicated in Figure 5 for the purpose of inserting dresses or shirts thereover. One or more sockets 36 is provided in the upper end of the support 8 in order to receive the post 37 of an iron 40 holder or stand 38. This stand is shown in plan view in Figure 6 although it may be of any configuration desired. The stand is simply lifted out of the socket and placed in the box or holder when not in use.

50 The table top is removed by first unfastening the hooks 31 and subsequently sliding the top sidewise until the stops 28 are clear of the lower edges of the rails 24. Then 55 the top may be tilted as indicated in Figure 3 as the stops will slide along the inclined ends of the rails and in fact the cooperation between the stops and the inclined ends will help to slide the table top completely off 60 the table. The upper skirting board may slide along the rails in order to take the weight off the operator as much as possible until the table top must be actually lifted from the table.

65 The removal of the top exposes the iron-

ing board for use and during this time the table top may be placed against the wall or in some other position where it will occupy but little space. The top is put back in place by reversing the operation already 70 described. The upper skirting board is slid along the rails until it arrives at the ends thereof when it will tend to descend by gravity and the stops will guide the top into proper final position.

75 It will be appreciated from the foregoing that all of the advantages and uses of both an ironing board and a library or other table are combined in the single piece of furniture and its conversion into one or the other may be accomplished quickly and easily. The attractiveness and appearance of the table are in no wise diminished and in fact the article forms a very neat and desirable piece of furniture.

80 It is obvious that various changes and modifications may be made in the details of construction and design of the above specifically described embodiment of this invention without departing from the spirit 90 thereof, such changes and modifications being restricted only by the scope of the following claims.

85 What is claimed is:

1. A combination table and ironing board 95 comprising end supports, an ironing board thereon, a table top having end skirting boards, rails secured to said end supports and projecting above the same for supporting the table top, said rails also projecting above the ironing board and said rails having downwardly converging ends, stops carried by the intermediate portions of the lower edges of said rails, cooperating stops carried by said skirting boards and adapted to project beneath said rails, and to encounter said first mentioned stops, said cooperating stops also adapted to engage the downwardly converging ends of said rails at one side in the act of fitting the top to 100 the table, and means to secure the table top against sliding movement on said rails.

105 2. A combination table and ironing board comprising substantially solid end supports, boards for spacing said end supports, one of said boards being laid substantially horizontally to form a base or bottom for a box and two other of the boards being erected as sides for the box, a tie-rod extending beneath the base board substantially centrally thereof and being secured to the end supports for drawing the end supports upon the ends of the boards, other tie-rods within the box and extending against the inner portions of the side boards for the box, an ironing board hinged to the upper end of one of said supports and adapted to rest at its free end upon the other support, rails secured to the outer sides of said supports and extending above the supports and above 110

the ironing board, said rails having downwardly and inwardly beveled ends, a tabletop detachably and slidably fitted upon said rails above the ironing board, cooperating 5 stops carried by the lower edges of said rails and by said table top, the stops adapted to meet to arrest the movement of the

table top, the stops carried by said table top adapted to engage the beveled ends of said rails whereby to guide the table top into 10 position on the rails, and means for holding the table top against sliding movement.

In testimony whereof I affix my signature.
OLIVETTE ROMESBERG.
